H. FELDMAN

HANGER FOR ELEVATOR DOORS

Filed June 30, 1926

UNITED STATES PATENT OFFICE.

HARRY FELDMAN, OF BROOKLYN, NEW YORK, ASSIGNOR TO THE PEELLE COMPANY, OF BROOKLYN, NEW YORK, A CORPORATION OF NEW YORK.

HANGER FOR ELEVATOR DOORS.

Application filed June 30, 1926. Serial No. 119,613.

My invention relates to hangers for elevator doors, and more particularly to hangers for the upper door sections of counterbalanced, semi-automatic or full automatic elevator doors employing a plurality of sections capable of moving in the same or in parallel vertical planes, and in opposite directions upon guides extending vertically upon opposite sides of the door openings in an elevator shaft.

Elevator doors of the type above referred to are manufactured in their entirety in the factory, and the parts thereof shipped to the point of installation, where erection gangs assemble the various parts and mount them upon the guide rails. This erection work usually occurs in buildings being constructed, the workmen being required to handle heavy door sections not only in mounting them upon the guides or guide rails, but when securing the flexible connections between the door sections and adjusting the lengths of the connections in a manner to secure the proper opening and closing movements of the door, and the locating of the door sections with relation to the opening, to conform to the requirements of various ordinances and Fire Underwriters' regulations. While ordinarily a rod and turnbuckle and a standard form of link chain construction is used as the connections between the two door sections, the turnbuckle is relied upon largely for readjusting the length of the connections in the event of stretch after continued use, and for perfecting an approximate adjustment secured when connecting the chains to the upper door sections and truing up the connections on opposite sides of the door.

With the above conditions in mind, I have provided a hanger for use upon the upper door section, the construction of which is such as to permit the quick attachment of a chain thereto in a manner which will distribute the load of the door sections throughout the hanger fitting and throughout a number of adjacent links in the chain so as to minimize likelihood of the breakage, either of the hanger or of the portions of the chain co-operating immediately therewith. The construction of this hanger is such as to admit of its being made of cast, malleable iron and of its being secured to the side bars of the door structure while in the factory.

While, if desired, the load of the door structure upon the chains may be relied upon to retain the chain in its operative relation to the hanger fitting, the construction of the fitting is such that means positively preventing escape of the chain therefrom may be employed without unduly increasing the bulk of the fitting or sacrificing any of the strength required to ensure permanency in the connection, by means of the fitting, between the chain and the door section. The construction is such that variance in the dimensions, either of different fittings or of different links of the chain, will not interfere with the co-operating relation between the fitting and the chains, and will also permit any portion of a standard chain to be used in connection with the fitting.

Hanger fittings embodying my invention are symmetrical as to the opposite ends thereof, so that the same fittings may be used upon either side of the door by a mere reversal of the fitting, each fitting being both right and left.

While the construction of the hanger fitting is such as to permit the quick connection of a chain with relation thereto, thus facilitating the initial adjustment in the length of the chain when installing the elevator doors, its construction is also such that in making the adjustment, if desired, the chain length between the door sections may be lengthened or shortened approximately one-half the length of a link. Such adjustment is desirable because of the frequent irregularities in the locating of door openings of a building as compared with the showing of such upon the architect's plans and resulting misplacement of sheaves, and stops in the guide rail structure.

The invention consists primarily in a hanger for elevator doors, embodying therein a fitting having spaced side webs thereon forming an approximately central, laterally enlarged pocket of about the length of the link plates of the chains, and an end channel leading therefrom of about the width of such plates, whereby the stresses from the load on said chain will be distributed to both of said side webs, and means whereby said fitting may be secured to the side bar of an elevator door; and in such other novel features of construction and combination of

parts, as are hereinafter set forth and described, and more particularly pointed out in the claims hereto appended.

Referring to the drawings,

Fig. 1 is a view of a counterbalanced elevator door structure condensed vertically and laterally, illustrating the application of a hanger of my invention to the upper door section, the hanger bar of the lower door section only being shown;

Fig. 2 is a view of the hanger fitting upon a larger scale;

Fig. 3 is a view of the fitting from the right of Fig. 2; and

Fig. 4 is a view similar to Fig. 2, but upon a smaller scale illustrating how the chain may be secured to the fitting in a manner to secure an adjustment of one-half the length of the longer links in the chain.

Like numerals refer to like parts throughout the several views.

In the embodiment of the invention shown in the drawings, 10 indicates the upper door section of a counterbalanced freight elevator door, and 11 the hanger bar of the lower door section, it being understood this hanger bar is permanently secured to, and forms a part of, the top bar of the lower door section.

At 12 are the wall angles and at 13 are the guide rail structures for the door sections, which are of the usual and well known construction, being shown in the drawings merely to illustrate the small space available for the handling of the chains when installing a door.

In older door constructions in older buildings, it was the practice to connect the chains toward the top of the upper door section, since in the old buildings the distance between floors was usually very much greater than in modern buildings, and the door openings themselves were very much smaller.

The section 10 moves upwardly, and the section carrying the hanger bar 11 moves downwardly upon the rails 13.

Following the usual practice, the opposite ends of the hanger bar 11 each have connected therewith a rod 14 forming a part of the connection between the door sections, this rod including therein a turnbuckle construction 15.

Connected to the upper end of each rod is a flexible, link chain 16 passing about a sheave 17 carried by each guide rail structure 12 and 13 respectively. The axes of the sheaves 17 are at right angles to the wall of the shaft, the pivots of the chain being parallel with these axes. The length of the connection between the upper door section and the hanger bar 11 is such as to have the two sections meet substantially centrally of the door opening and provide the required overlapping of the upper and lower door sections and the lintel and sill of the door opening. The sheaves 17 are located on the guide rail structures 12-13 with relation to this meeting point of

the two door sections, and since the layout of the rail structure including the sheaves and their assembly is made ordinarily from architectural plans, any variation in the locating of the door opening from such plans requires adjustment in the length of the flexible connections which may be done either by varying the point of the chain which is connected with the door section, or by actuating the turnbuckles 15.

Upon the opposite side bars of the upper door section 10, I firmly secure hanger fittings 18, these fittings ordinarily being mounted upon the bars toward the bottom of the door section so as to permit a run of a sufficient length of chain 16 about the sheaves 17, to allow a full opening movement of this door section, and bring the astragal thereof close to the lintel of the door. This fitting 18 comprises a flange 19 having rivet or bolt openings therein by means of which the fitting may be secured to the side bars of the door section. At one edge of this flange, I provide an angular flange 20 projecting from the side bar toward the guide rail to an extent to bring it in substantially the proper relation to the sheaves 17 to ensure a free running of the chain 16 during the opening and closing movements of the door.

The flange 20 has oppositely disposed side webs 21 and 22, spaced apart to permit the passage of the chain 16 therethrough in a manner to be hereinafter described. The contour of the webs 21 and 22 is such as to form a laterally enlarged pocket 23, the greatest width of which is about that of the length of the link plates in the chain 16, the walls of the webs at this point being curved to conform substantially to the curvature of such links.

Leading from the enlargement 23, substantially along the center line of this enlargement, are constricted channels 24 and 25, the webs forming the opposite walls of which being curved substantially as shown. The width of the channels 24 and 25 is about that of the narrowest dimension of the link plates of the chain 16.

The ogee contour of the walls of the webs 21 and 22 adjacent the constricted channels 24 and 25 is for the purpose of allowing certain play in the portion of the chain co-operating with the fitting in order to secure a more effective distribution of the stresses resulting from the load transmitted to the fitting through the chain.

The webs 21 and 22 adjacent the channels 24 and 25 are extended as shown clearly in Fig. 3, beyond the point where stresses are transmitted to the hanger fitting, to form lugs 26 having openings therein to receive cotter pins 27, or other means passing across the channels 24 and 25 for preventing any possible escape of the chain from the fitting as a result of the violent jars and impacts to which doors of this character are subjected.

By providing the opposite channels 24 and

25 in the hanger fitting, such fittings may be used upon either side of the door by merely reversing the fitting. This construction also permits the end of the chain to pass entirely 5 through the fitting, thus avoiding any great nicety as to the length of chain used, and permitting adjustment of its length without cutting of the chain. It also permits the nesting of the chain, either in the manner shown in 10 Fig. 2, which practice, if followed, will permit adjustment equaling only the length of the link plates, in the chain, or the manner of nesting as shown in Fig. 4, which permits an adjustment amounting to approximately one- 15 half of the length of such links.

With the construction of fitting described, a chain may be readily flexed to the desired position and adjoining links slipped within the pocket or enlargement 23 and the con- 20stricted channels 24 and 25, the mere position- 25ing of these links securing an effective inter- lock between the fitting and the chain. By having the pocket or enlargement and channels of slightly larger dimensions than those of the link plates of the chain, ease in the fitting of the links of the chain is assured, and nicety in the proportioning of the pocket and channels is avoided, thus permitting the 30 production of the fittings by ordinary casting operations and avoiding the necessity of machine work upon these fittings.

Assuming that the connection is of the form shown in Fig. 2, an outer link of the chain will be seated in the pocket 23, one adjacent outer link will be fitted in the upper channel 24 and the other adjacent outer link will be 35 fitted in the lower channel 25.

With the parts in this position, when the load of the door sections comes upon the 40 chains, the link in the channel 24 will have a sliding vertical movement in relation to the fitting, thus causing the connecting link between it and the link in the pocket 23 to pivot 45 against the side web 21 above the pocket 23, and thus impart a lateral thrust through the link in said pocket against the portion of the web 22 forming the lower part of said pocket 23, the link in the pocket 23 having a slight 50 tilting movement. The slight pivotal move- 55ment of the link connecting the one seated in the channel 24 and the one seated in the pocket 23 will also have the effect of thrusting the lower end of the link in the channel 24 against the web 22 and the link below that seated in the pocket 23 will be thrust against the web 21.

In this manner the loads upon the chain will be distributed to both webs 21 and 22 at points 60 of these webs where there is the greatest mass of metal, and wear upon the chain will also be distributed throughout the various links of the chain above referred to, so that even with considerable wear of the chain there will be an automatic readjustment in the relation of

the fitting and the links of the chain co-oper- 65 ating directly therewith.

With the mounting of the chain in the man- 70ner shown in Fig. 4, the conditions will be the same as heretofore described, since with this arrangement inner or connecting links are seated in the enlargement or pocket 23 and the channels 24 and 25, and the outer links extend upon the opposite sides of the links in the 75 pocket to within the said channels, thus acting as levers in the manner above described.

If it be desired to adjust the length of the chain with the relation of parts shown in Fig. 2, an adjustment amounting to the length of one or more full links must be made. When 80 changing the relation of parts from that shown in Fig. 2 to that shown in Fig. 4, an adjustment of approximately one-half the length of a link may be made.

While under normal conditions the direc- 85tion of the stresses through the chain upon the fitting 18 is such as to avoid likelihood of the escape of the chain from between the side webs 21 and 22, as a safeguard against tam- 90pering with the chains or displacement of the chains with relation to the fitting by abnormal 95 conditions, I preferably provide the cotter pins 27 passing through the openings in the lugs 26 and across the channels 24 and 25 re- 100spectively. These pins are subject to no sub- 105stantial strains and serve as an effective barrier. It is to be noted that the lugs 26 are at one side of the points of contact of the links of the chain with the webs 21 and 22 so that the holes for the cotter pins do not weaken 110these webs so far as the sustaining of the load of the door is concerned.

The fittings 18 as heretofore stated, may be 115 of sandcast, annealed iron, since the ordinary markings of the mold do not interfere with the use of such fittings, provided the castings are fairly clean. In fact, clearance between the links of the chain and the walls of the webs is necessary to secure the desired grip- 120ping action as a result of the movement of the links as described, this clearance being suffi- 125ciently great to compensate for slight imper- fects in the casting. Care should be taken to have the flange 20 and the webs 21 and 22 sufficiently heavy to withstand the maximum strains to which they will be subjected, al- though fittings of the same dimensions may be used with a considerable range in the sizes of different doors so as to permit the standardi- 130zation of this part as to all doors produced. The weight of the fittings is not great, but this is immaterial since in the type of doors herein referred to, the addition of weight to one sec- 135tion or the other is necessary either to secure an approximate balance of the two sections of the door, or the overweighting of one of these sections in relation to the other.

While I have described the hanger fitting in connection with special types of doors,

the conditions during the erection of which are such as to make the fitting particularly desirable, it is not my intention to limit the use of the fitting with such doors, particularly since its use, if desired, may be extended to other types of doors.

It is not my intention to limit the invention to the precise details of construction and arrangement of parts shown in the drawings, it being apparent that such may be varied without departing from the spirit and scope of the invention.

Having described the invention, what I claim as new and desire to have protected by Letters Patent, is:—

1. A hanger for elevator doors, embodying therein a fitting having spaced side webs thereon forming an approximately central, laterally enlarged pocket of about the length 20 of the link plates of the chains, and an end channel leading therefrom of about the width of such links, whereby the stresses from the load on said chain will be distributed to both of said side webs, and means whereby said fitting may be secured to the side bar of an elevator door.

2. A hanger for elevator doors, embodying therein a fitting having spaced side webs thereon forming an approximately central, laterally enlarged pocket of about the length 30 of the link plates of the chains, and end channels of about the width of such links leading respectively from the top and the bottom of said pocket, whereby the stresses from the load on said chain will be distributed to both of said side webs, and means whereby said fitting may be secured to the side bar of an elevator door.

3. A hanger for elevator doors, embodying therein a fitting having a flange whereby the fitting may be secured to the side bar of an elevator door, an angular flange carried thereby, and side webs upon said angular flange forming an approximately central, laterally enlarged pocket of about the length 45 of the link plates of the chains, and an end channel leading therefrom of about the width of such links, whereby the stresses from the load on said chain will be distributed to both of said side webs.

4. A hanger for elevator doors, embodying therein a fitting having a flange whereby the fitting may be secured to the side bar of an elevator door, an angular flange carried thereby, and side webs upon said angular flange forming an approximately central, laterally enlarged pocket of about the length 55 of the link plates of the chains, and end chan-

nels of about the width of such links leading respectively from the top and the bottom of said pocket, whereby the stresses from the load on said chain will be distributed to both of said side webs.

5. A hanger for elevator doors, embodying therein a fitting having spaced side webs thereon forming an approximately central, laterally enlarged pocket of about the length of the link plates of the chains, an end channel leading therefrom of about the width of such links, whereby the stresses from the load on said chain will be distributed to both of said side webs, and lugs upon said side webs projecting beyond said channel, means adapted to pass through said lugs and across said channel to prevent the escape of a chain from said channel and said pocket, and means whereby said fitting may be secured to the side bar of an elevator door.

6. A hanger for elevator doors, embodying therein a fitting having spaced side webs thereon forming an approximately central, laterally enlarged pocket of about the length of the link plates of the chains, end channels of about the width of such links leading respectively from the top and the bottom of said pocket, whereby the stresses from the load on said chain will be distributed to both of said side webs, and lugs upon said side webs projecting beyond said channels, means adapted to pass through said lugs and across said channels to prevent the escape of a chain from said channels and said pocket, and means whereby said fitting may be secured to the side bar of an elevator door.

7. A hanger for elevator doors, embodying therein a fitting having a flange whereby the fitting may be secured to the side bar of an elevator door, an angular flange carried thereby, and side webs upon said angular flange forming an approximately central, laterally enlarged pocket of about the length of the link plates of the chains, end channels of about the width of such links leading respectively from the top and the bottom of said pocket, whereby the stresses from the load on said chain will be distributed to both of said side webs, and lugs upon said side webs projecting beyond said channels, means adapted to pass through said lugs and across said channels to prevent the escape of a chain from said channels and said pocket.

In witness whereof I have hereunto affixed my signature, this 25th day of June, 1926.

HARRY FELDMAN.
